LUG STRAP

Harry F. Webster, Warren, Ohio

Application October 4, 1938, Serial No. 233,200

1 Claim. (CL 139—153)

This invention relates to improvements in lug straps of a laminated construction wherein superimposed plies of fabric are united by a bonding material. More particularly the invention relates to improvements in such a lug strap constructed of rubberized fabric.

Important objects of the invention are, to provide a lug strap of the aforesaid type constructed to give it great durability, and provide such a strap designed for economical manufacture.

Other objects of the invention will appear hereinafter.

In the drawing,
Fig. 1 is a perspective view showing a step in the manufacture of the improved lug strap;

Fig. 2 is a perspective view showing another step of said manufacture;

Fig. 3 is a perspective view of a filler block employed in the lug strap construction;

Fig. 4 is a view of a double lug strap structure prepared for molding.

Fig. 5 is a longitudinal sectional view illustrating the molding of a double strap;

Fig. 6 is a transverse section on the line 6—6 of Fig. 5;

Fig. 7 is a perspective view of a mold core employed in the molding of the double strap; and

Fig. 8 is a perspective view of a finished lug strap.

In the manufacture of lug straps embodying the improved construction there is employed a wide sheet 1 of strong square-woven textile fabric. Both sides of said sheet are coated with a bonding material 2 which is preferably an uncured rubber composition capable of being vulcanized to a hard state and having a low viscosity prior to vulcanization.

The sheet 1, coated with the uncured bonding material, is wound around a flat core 3 whose cross section is similar to the interior of a loop defined by placing two U-shaped lug straps end to end. As the sheet is wound it is kept taut for smoothness and close contact of its coils. The winding is continued to form a number of superimposed plies sufficient to build-up the structure to a thickness exceeding the desired thickness of the longitudinal side members or legs of a finished lug strap. The sheet should be wound with its warp threads running straight lengthwise of the windings, around the core 3. The wound sheet forms a flat, multi-ply sleeve. This sleeve is removed from the core 3 and severed along transverse lines 4 equally spaced along the sleeve to thereby obtain a multitude of elongated flat loops 5 each conforming approximately to a pair

of lug straps arranged end to end. Preferably the width of each partly formed double strap 5, between the lines 4, slightly exceeds the desired width of a finished strap.

A number of sheets 6 of strong textile fabric are coated upon both sides with a bonding material. Preferably this material is also a rubber composition similar to that upon the sheet 1. The rubberized sheets 6 are superimposed smoothly one upon another in a required number to produce a multi-ply sheet having a thickness approximately equal to the inside width of the loop defined by one of the aforesaid double straps. The sheets 6 are smoothed and pressed together by rolling or otherwise. Next said multi-ply sheet is severed along spaced parallel lines 7 and along spaced parallel cross lines 8 to divide the sheet into a multitude of multi-ply blocks 9 of approximately cubical form.

A pair of the blocks 9, with their bonding material still uncured, are fitted within the opposite ends or bows of one of the double straps 5 in such position that the plies 9a of the blocks are parallel to the side members of the strap, and the opposite sides of the blocks are flush with the opposite side edges of the strap.

The double strap, with the inserted filler blocks is next molded and vulcanized. In preparation for molding, a mold core 10 of steel is fitted into the loop defined by the strap. This core should have the precise shape and dimensions desired for the interior of the molded strap. As shown, the core has flat sides and concave end surfaces 11. These concave surfaces are engaged with the inner or forward surfaces of the blocks 9. The strap, with the core inserted, is placed between opposed block-like sections 12 of a split mold. Said mold sections have, in their opposed faces, similar cavities 13. These cavities are elongated, have flat sides and rounded ends, and conform exactly to the shape and dimensions desired for the molded strap. The plane of separation of the mold sections is at the center of the bows or ends of the looped strap. The molding operation is performed under heat and pressure to vulcanize the rubber composition to a preliminary soft rubber state. Under the heat and pressure the rubber composition of the filler blocks unites with that of the strap, and all of the plies forming the strap and the filler blocks are permanently united to form an integral double lug strap unit. The forward surfaces 14 of the blocks are also molded to convex curvature by the concave ends of the mold core.

After said molding and preliminary vulcaniza-

tion the strap and core 10 are removed from the mold, the core 10 is removed from the strap, the strap is cooled, and excess, overflow rubber is trimmed off. The double strap is severed at the 5 middle of its length to form two single straps S, one of which is shown in Fig. 8. The ends of the legs of the strap are cut to a rounded form and, either before or after severance, the usual slots 15 are cut in the side members or legs of the strap. Finally the vulcanization of the rubber 10 is completed to bring it to a hard state. This may be done by subjecting the completely formed straps to dry heat in a suitable oven.

The lug strap, so produced, has a thickened, 15 reinforced bow structure to withstand impact with the picker stick. The reinforcement is a permanent, integral part of the strap and the arrangement of the plies 9^a contributes materially to wear resistance. Said plies impact the 20 picker stick edgewise, which is superior to broadside impact because then the picker stick would wear through the thickness of the plies and fray the impact surface. The convexity of said surface enables it to make rolling contact with the 25 picker stick. Since the fabric employed throughout the structure of the strap is coated upon both sides with the rubber composition and since the composition is confined in the molding operation the finished strap contains much more of the 30 composition than is required for mere bonding. It comprises a large part of the strap and forms a matrix extending throughout the entire strap and enveloping all of the fabric. This matrix is hard, tough, resilient and moisture-impervious. 35 It surrounds the individual threads of the fabric and is reinforced throughout the legs and the thickened bow of the strap by the fabric plies.

It is common practice in lug strap construction to first completely form the U-shaped body of 40 the strap and then insert within the bow of the strap a separately formed plug to serve as an

abutment for the picker stick. Said plug is riveted in place with consequent weakening of both the strap and the plug. My invention avoids this objectionable construction and provides a durable, one-piece, molded lug strap adequately reinforced to resist wear from the picker stick and inexpensive to manufacture. 5

What I claim is:

A lug strap comprising numerous superimposed long plies of rubberized fabric all extending 10 widthwise from edge to edge of the strap and extending longitudinally in U-form and in nested relation and bonded together in succession by the rubber to form the legs and bow of the strap, and numerous superimposed short plies of rubberized fabric nested within the bow and between the portions of the legs adjacent the bow and forming a filler increasing the fore-and-aft thickness of the bow, all of said filler plies extending substantially the full width of the strap 20 between the edges of the latter and all lying substantially parallel to the plies in the legs of the strap and bonded together in succession by the rubber and with their outermost plies bonded by the rubber to the inner faces of the legs and their rear edges bonded by the rubber to the inner face of the bow and with their forward edges disposed to form an abutment to engage the picker stick, said legs, bow and filler being 25 permanently united by molding and vulcanization into a solid, hard rubber mass with parallel layers of fabric embedded in the rubber and extending side by side throughout the legs and the reinforcement in the bow, with the edges of the fabric 30 layers in said reinforcements in position to engage the picker stick edge-on, to form a one-piece integral lug strap structure with the filler held in place solely by the molded and vulcanized rubber. 35
